US00D739212S

(12) **United States Design Patent**
Miller

(10) **Patent No.:** **US D739,212 S**
(45) **Date of Patent:** **** Sep. 22, 2015**

(54) **HOUSING OF A ROPE GRAB**

(71) Applicant: **D B Industries, LLC**, Red Wing, MN (US)

(72) Inventor: **Rick G. Miller**, Hastings, MN (US)

(73) Assignee: **D B Industries, LLC**, Red Wing, MN (US)

(**) Term: **14 Years**

(21) Appl. No.: **29/490,444**

(22) Filed: **May 9, 2014**

CLAIM

The ornamental design for a housing of a rope grab, as shown and described.

DESCRIPTION

FIG. 1 is a first side perspective view of a housing of a rope grab of the present invention;

FIG. 2 is a second side perspective view of the housing of a rope grab shown in FIG. 1;

FIG. 3 is a front view of the housing of a rope grab shown in FIG. 1;

FIG. 4 is a rear view of the housing of a rope grab shown in FIG. 1;

FIG. 5 is a top view of the housing of a rope grab shown in FIG. 1;

FIG. 6 is a bottom view of the housing of a rope grab shown in FIG. 1;

FIG. 7 is first side view of the housing of the rope grab of FIG. 1; and,

FIG. 8 is a second side view of the housing of the rope grab of FIG. 1.

The broken lines showing portions of the housing of a rope grab are for the purpose of illustrating portions that form no part of the claimed design.

1 Claim, 6 Drawing Sheets
